Application August 15, 1944, Serial No. 549,582

7 Claims. (Cl. 153—60)

1

The invention relates to cross-roll straightening machines, machines, that is to say, embodying cross-rolls for the hot or cold rolling or straightening of bars, rods, shafts, pipes, tubes, and other sections.

Ordinarily, a cross-roll straightening machine includes several passes comprising each a plurality of cross-rolls, and the rolls of each pass are relatively adjustable, to adapt the machine for different sizes and sorts of work. In general the invention is directed to certain refinements and elaborations in cross rolling machines, in consequence of which the required adjustments may be more readily and accurately effected.

More particularly the invention is applicable to and effective in large tube-straightening machines—machines adapted to process tubes and pipes of large diameter. In a large machine of this kind there is a tendency for the rolls to distort the walls of the tubes being treated, and I have found that four rolls may be so organized in each pass that the harmful effects of this objectionable tendency are eliminated. My invention contemplates an arrangement of each cross-roll pass in which the position of the rolls and their mounting means are at least approximately symmetrical about the center of the stock acted upon, and in which the distorting pressure of the rolls is minimized by a symmetrical or approximately symmetrical load application to the stock.

A further consideration is the provision of suitable driving means for large, contoured cross-rolls arranged in the above-mentioned multiple organization.

The invention still further embraces improved roll-driving means, and improved means for adjusting the rolls of each pass, and for adjusting the passes themselves relatively to one another. While the present improvements are applicable to cross rolling machines in general, they are particularly advantageous in a large tube-straightening machine of the sort mentioned, and in such embodiment the invention is hereinafter described.

In the accompanying drawings Fig. I is a view in side elevation of such machine; the machine will ordinarily be mounted upon a heavy concrete base extending below floor level, and in Fig. I such a base is shown in vertical section. Fig. II is a view in cross section of the machine and base, taken on the plane II—II of Fig. I. Fig. III is a phantom view, illustrating, on the plane III—III of Fig. II, the three roll passes which in this case the machine includes. Fig. IV is a fragmentary

view, showing to larger scale a single cross-roll, its supporting yoke, and the adjusting means and driving elements associated therewith; the parts shown in Fig. IV appear partly in side elevation and partly in section on the plane IV—IV of Fig. II. Fig. V is a fragmentary view, showing a yoke and cross-roll assembly to still larger scale, and showing the yoke partly in elevation and partly in axial section. And Fig. VI is a fragmentary, sectional view, taken on the plane VI—VI of Fig. I.

Referring to Figs. I and II, the reference numeral 1 indicates the concrete base upon which two opposed bed members 2 are firmly supported, and reinforced by cross-ties 2a. Three housings or auxiliary frames 3, 3, 3 are borne upon the opposite bed members 2, and each housing includes four cross-rolls 4 which form one of the three roll passes of the machine. The concrete base is recessed, as shown, to provide clearance for portions of the machine extending downward, between the bed members 2, and below floor level.

The manner in which a cross rolling machine operates to straighten or roll down rounds (a round being stock of round cross section) is generally known in the art; the powerfully rotated cross rolls of the several passes exert lateral pressure upon the stock, and helically propel it through the machine, as the arrows on tube T indicate in Fig. III. The pass line of the intermediate group or pass of rolls of a cross-roll straightening machine is offset laterally from the normal pass line PL of the machine, the normal pass line being considered a straight line extending through the centers of the entering and leaving roll passes, to deflectingly act on stock traveling through the machine. Thus, the stock is laterally bowed as it helically advances between the entering and leaving roll passes of the machine. The effect of such known treatment is to straighten and true the stock.

While the cross-rolls are so shaped or contoured that in known manner they engage the stock in lines of contact of substantial lengths, such extended lines of contact are ineffective in the case of large tubes (in which the ratio of the tube diameter to its wall thickness commonly is great) to inhibit the objectionable tendency of the tube walls to bulge and become distorted under the influence of the inwardly directed pressures of the rolls. That is to say, the walls of a tube under the pressure of cross-rolls tend to bulge circumferentially outward between the points or lines of contact of the rolls with the tube. In overcoming this objection, four cross-rolls 4 are pro-

vided; the four rolls are substantially equispaced about the pass line upon which the tube T (Fig. II) is advanced, and advantageously all four rolls of the pass are powerfully rotated.

In operating upon heavy work of the sort under present consideration, the lateral, flexing thrust A (Fig. III) of the intermediate pass, and the opposing thrusts B—B of the entering and leaving passes are of relatively great magnitude. The usual cross-roll straightening machines employ only two cross-rolls in each pass, and it appears that the rolls and supports therefor of such a machine cannot be designed to withstand the strains, certainly not without going to extremely heavy and costly construction. In providing four cross-rolls in each pass the lateral thrusts (A and B) are advantageously divided between two rolls. The arrows B' and B'' in Fig. II illustrate how the lateral thrust B of the leaving pass is divided between two cross-rolls.

To adapt the machine for various sizes of tubes, the rolls 4 of each pass are adjustable radially of the pass line of the machine, and, as will presently appear, means are provided to effect radial adjustment of the rolls of a pass.

It is further desirable that the degree of tube flexing shall be varied to suit different sizes of tubes, and such variation in degree of flexing is obtained by adjusting the rolls of the intermediate pass or group of rolls transversely or vertically of the machine. As shown in Figs. I and VI, the housing or frame 3 of the intermediate pass of rolls includes integral brackets 3a which slidably rest upon the opposite bed members 2, and such organization, while providing the desired sturdy support for the housing and its rolls, admits of the adjustment of the housing between the bed members, that is, transversely of the normal pass line of the machine, as indicated by arrows a in Fig. III. Upon the upper faces of the bed members 2 are secured guides 5, serving in conjunction with the brackets 3a to maintain the intermediate roll housing 3 in fixed position longitudinally of the pass line, while providing adjustment of its pass out of alignment with the primary line of the pass as defined in the entering and leaving roll groups.

Again turning to Fig. VI, means for effecting the transverse adjustment of the intermediate housing 3 are illustrated. Such means comprise a threaded shaft 6 rotatably secured to the housing 3 at 7, and extending in threaded engagement with a sleeve or nut 8 secured to the adjacent bed member 2. The shaft 6 includes a journal portion 6a upon which a gear 9 is slidably keyed; a pinion 10, responsive to the rotation of a hand wheel 11 in either direction, is effective to rotate the gear 9 in either direction of rotation, whereby the shaft 6, turning within fixed sleeve or nut 8, is effective to shift the housing 3 transversely of the pass line. The brackets 3a that ride the opposite bed members 2 are provided with slots 3b, through each of which a lock-bolt 12 extends; the lower end of each lock-bolt is secured in the underlying body of the supporting bed member, 65 and the upper end of the bolt carries a nut 13, lying above the slot 3b. Normally, the nuts 13 are tightened on the bolts 12, and the brackets 3a are thereby securely fixed upon the bed members 2, but, upon loosening the nuts, the housing 70 3 may be adjusted in the manner explained.

Additional locking means may be organized with the screw shaft 6, and such means may comprise an externally threaded sleeve 14, slidably keyed to the shaft portion 6a. The sleeve 75

includes a flange 14a adapted to engage the inner face of a housing 15 for the gearing 9, 10, and a lock-nut 16 is arranged on the threaded sleeve externally of such housing. Normally, the lock-nut 16 lies tight against the external face of housing 15, and the flange 14a is held forcefully against the inner face of the housing, whereby the sleeve is locked in fixed position, and the shaft 6 keyed thereto is held against rotation. Alternately, when the lock-nut is loosened, the sleeve 14 may idly rotate, and the shaft 6 may be operated for effecting adjustment of the intermediate housing 3.

Obviously, the adjustment of the intermediate roll group, by simple modification well within the knowledge of an engineer skilled in the art, may be provided by vertical rather than transverse adjustment of the housing for the intermediate roll group.

Still another adjustment of the machine is desirable. As indicated by the arrows b in Fig. III, the entering or leaving passes of rolls, or desirably both of such passes, are adjustable longitudinally of the pass line PL. The housings 3 of the entering and leaving passes include side brackets 3c which rest upon the bed members 2 and are slidably longitudinally thereof. As shown in Fig. I, threaded shafts 17 are rotatably fixed in stationary journals 2b on opposite ends of the bed members 2; these shafts 17 severally extend in threaded engagement with lugs 3d integrated with the brackets 3c of the housings 3, whereby rotation of the shafts will produce movement of the housings longitudinally of the machine. Conveniently, a shaft 17 is arranged on each side of the housings 3, as shown in Fig. II, and, as appears in Fig. I, the shafts organized with the entering roll housing are rotatable, by means of hand wheels 18, independently of the shafts 17 that control the leaving roll housing. The two shafts 17 of each housing 3 are interconnected to rotate in unison, and sprocket chains 19 (extending in the line of sight in Fig. I) afford means to this end. Thus, the entering or leaving pass of rolls may be adjusted as a unit relatively to the intermediate pass and longitudinally of the pass line of the machine.

In further accord with the invention each of the driven cross-rolls 4 is provided with its own, independent driving motor 40 which is organized in unit assembly with the yoke 400 in which the roll is trunnioned, as shown in Figs. IV and V. Each roll-supporting yoke 400 includes a hollow spindle 401 which extends perpendicularly to and centrally of the axis of the supported roll 4, note Fig. IV. The yokes 400, supported by the spindles 401 in secure engagement with the roll housings 3, are severally adjustable angularly and axially of their spindles 401; that is, the rolls 4 are adjustable radially of the pass line of the machine, and the angularity of the roll axes with respect to such pass line may be varied. Means for effecting such adjustment of the yokes 400, and in consequence the cooperative relation of the rolls, will presently be described.

Advantageously, the roll housings 3 are formed of substantially duplicate segmental sections 30 which are secured end-to-end, say by means of bolts 31 (Fig. II). There being four rolls in each pass in this case, each housing 3 comprises four housing sections 30, and, as may be perceived in Figs. II and IV, each roll, its supporting yoke, and its driving motor are secured in unit assembly with a housing section 30. Thus, each roll

pass of the machine comprises four unit assemblies comprising a housing section 30, yoke 400, motor 40 and roll 4, and each of such unit assemblies is a duplicate of another. Indeed, a roll pass may thus be constructed of four identical units, and the three roll passes of the machine may be formed by twelve identical units arranged in three groups, and assembled upon the bed elements 2.

The rotary drive shaft 41 of each motor 40 extends through the hollow supporting spindle 401 of the roll it drives, and Fig. V shows how a train of reduction gears 42 are connected to the neck 43 of roll 4; bevel gears 44 and cross shaft 45 transmit rotation from power shaft 41 to the gears 42, whereby the roll is powerfully rotated by its own driving motor. It will be understood, therefore, that each driven roll of the machine is provided with its own, mechanically independent driving unit 40, and that by regulating the R. P. M. of the several motors the peripheral speeds of the rolls may be severally adjusted in a manner which cannot be achieved readily, if at all in a machine having a main drive shaft to which several rolls are geared. More importantly, the driving organization adapts itself readily to different peripheral roll speeds in the several roll groups of the apparatus, which adaptability is useful in performing a polishing operation on the stock by pulling it through the apparatus by increased peripheral roll speed in successive passes. While the driving units 40 are mechanically independent, they are subject to common electric control. That is to say, the operation of the several driving units 40 is susceptible of electrical coordination, by means of well-known electric devices which in themselves form no part of the present invention, and, therefore, are not illustrated.

Referring particularly to Fig. IV, it will be seen that each housing segment 30 includes a plurality of roll-adjusting screws 32 that extend parallel to the stem 401 of the yoke installed in such housing segment; the several screws 32 are spaced apart circumferentially of the spindle 401, and severally make threaded engagement with bushings 33 secured in the housing segment. At its outer end the spindle 401 is integrated with a flange member 34, upon which the motor 40 is mounted; the flange 34 carries a plurality of set-screws 35 that project through the body of the flange, and bear against a "floating" ring 36. The outer ends of the yoke-adjusting screws 32 normally abut the ring 36, while the inner ends of the screws 32 bear against the face 402 of the yoke, and it is manifest that, by tightening the set-screws 35 against the ring 36, the spindle 401 is drawn to the right (Fig. IV), and the face 402 of the yoke is pressed forcefully against the inner ends of adjusting screws 32, while the ring 36 is urged with equal and opposite force against the outer ends of said screws 32. Thus, the structure engages with clamping effect the opposite ends of the adjusting screws 32, and, such screws being normally stationary in housing segment 30, the yoke is rigidly held in adjusted position. Conveniently, the set-screws 35 carry nuts 37, to lock the set-screws in their normally tightened positions.

It will be understood that, by loosening the set-screws 35, the pressure on ring 36 is relieved, and the clamping pressure of the yoke face 402 against the inner ends of the adjusting screws 32 is interrupted, whereby the spindle 401 may be turned in the housing 30, and the angular posi-

tion of the yoke 400 varied. Thereupon, the set-screws 35 are again tightened, and the yoke with its cross-roll 4 is secured in desired position of angular adjustment.

It is desirable that the yoke 400 shall be further adjustable, to the end that, for reasons already mentioned, the position of the cross-roll 4, radially or laterally of the pass line of the machine, may be regulated. Still considering Fig. IV, a pinion gear 38 is mounted upon each of the unthreaded portions 32a with which the yoke-adjusting screws are provided; each pinion gear 38 is held against lateral movement in a housing 39, and the gear is slidably feathered to the journal portion 32a of the screw with which it is associated; the several pinion gears 38 mesh in common with a ring gear 50 that is idly mounted upon the hollow spindle 401, and, manifestly, by rotating one of the screws 32 in housing segment 30, all screws 32 are caused to rotate in unison therewith. Movement of the screws in one direction of rotation or the other causes such screws to travel in unison laterally of the housing segment 30, to the right or to the left (Fig. IV), depending upon the direction of screw rotation. Accordingly, the yoke and motor assembly (400, 401, 40), by embracing the opposite ends of the screws 32 in the manner explained, is adjusted axially of the spindle 401, i. e. the roll 4 is adjusted radially of the pass line of the machine. Of course, the set-screws 35 may be loosened, more readily to admit of the rotation of the adjusting screws 32, and when an adjustment has been effected the set-screws are again tightened.

Advantageously, all four rolls 4 of a pass are adapted to be adjusted in unison, whereby they may be moved in synchronism radially inward or outward of the pass line, as the jaws of a rotary chuck are movable relatively to the axis about which a piece of work is to be rotated in a machine tool, say in a lathe. To this end one of the adjusting screws 32 of each yoke carries a bevel gear 51. As shown in Fig. II, the bevel gears 51 of the several yoke and motor assemblies of a pass of rolls are interconnected, by means of bevel gears 52, connecting shafts 53, 55, and universal joints 54. The shaft 53 is equipped with a hand wheel 56; rotation of such hand wheel is effective to rotate in unison all of the adjusting screws 32 of the four yokes in the pass of cross-rolls, and, manifestly, all rolls 4 of the pass are thus susceptible of adjustment in concert, in the manner described in the forepart of this specification.

Various structural modifications may be made by any skilled worker in the art of cross-roll straightening machines without substantial modification in those elements of my machine organization in which novelty primarily resides, and having exemplified my invention by showing and describing one apparatus embodiment thereof, that invention is to be limited only by the statement of the claims appended hereto.

65 I claim as my invention:

1. A cross-roll straightening machine having plural four-roll passes; each pass assembly comprising a frame, means for mounting four cross-rolls with approximately equal angular spacing in said frame concentrically with the center line of a pass formed by the said rolls for the reception of round stock therebetween and means for driving at least one roll of said pass; means for adjusting at least one pass assembly as a whole transversely of the machine with respect

to the pass line of the machine deflectingly to act on stock travelling through the machine, and means for adjusting at least one pass assembly as a whole longitudinally of the pass line.

2. A cross-roll straightening machine having at least three four-roll passes; each pass assembly comprising a frame, means for mounting four cross-rolls with approximately equal angular spacing in said frame concentrically with the center line of a pass formed by the said rolls for the reception of round stock therebetween and individually powered driving means for the said four rolls of the pass assembly; and means for adjusting one pass assembly as a whole transversely of the machine with respect to the pass line formed by the other two pass assemblies of the machine deflectingly to act on stock travelling through the machine.

3. A cross-roll straightening machine having at least three four-roll passes; each pass assembly comprising a frame, means for mounting four cross-rolls with approximately equal angular spacing in said frame concentrically with the center line of a pass formed by the said rolls for the reception of round stock therebetween and means for driving at least one roll of said pass; and means for adjusting one pass assembly as a whole transversely of the machine with respect to the pass line formed by the other two pass assemblies of the machine deflectingly to act on stock travelling through the machine.

4. In a cross-roll straightening machine having plural four-roll passes; a pass assembly comprising a frame, means for mounting four cross-rolls approximately equidistantly in said frame concentrically with the center line of a pass formed by the said rolls for the reception of round stock therebetween, individually powered driving means for the said four rolls of the pass assembly, and means for adjusting at least one pass assembly as a whole longitudinally of the pass line deflectingly to act on stock travelling through the machine.

5. A cross-roll straightening machine having plural four-roll passes; each pass assembly comprising a frame, means for mounting four cross-rolls with approximately equal angular spacing in said frame concentrically with the center line of a pass formed by the said rolls for the reception of round stock therebetween and individually powered driving means for the said four rolls of the pass assembly; means for adjusting at least one pass assembly as a whole transversely of the machine with respect to the pass line of the machine deflectingly to act on stock travelling through the machine, and means for adjusting at least one pass assembly as a whole longitudinally of the pass line.

6. A cross-roll straightening machine having at least three four-roll passes; each pass assembly comprising a frame, means for mounting four cross-rolls with approximately equal angular spacing in said frame concentrically with the center line of a pass formed by the said rolls for the reception of round stock therebetween and means for driving at least one roll of said pass assembly; and means for adjusting one pass assembly as a whole out of pass alignment with the other pass assemblies deflectingly to act on stock travelling through the machine.

7. A cross-roll straightening machine having at least three four-roll passes; each pass assembly comprising a frame, means for mounting four cross-rolls with approximately equal spacing in said frame concentrically with a pass formed by the said rolls for the reception of round stock therebetween and individually powered driving means for the said four rolls of the pass assembly; and means for adjusting one pass assembly as a whole out of pass alignment with the other pass assemblies deflectingly to act on stock travelling through the machine.

JOHN BLAIR SUTTON.
